EDWARD F. FIEDLER, OF WAUWATOSA, WISCONSIN, ASSIGNOR TO CLUM MANUFACTURING COMPANY, OF MILWAUKEE, WISCONSIN, A CORPORATION OF WISCONSIN

IGNITION-CIRCUIT-CONTROL MECHANISM

Application filed February 8, 1928, Serial No. 252,752.

This invention relates to improvements in ignition circuit control mechanism.

This application is a companion to application Number 209,568, filed July 30, 1927, and 5 discloses improvements in similar mechanism for controlling the circuit breaker mechanism by means of a remote key operated lock.

The cable wire extending from the lock to the circuit breaker engaging mechanism is 10 closed by a flexible sheathing having a minimum inner dimension which increases as the sheathing is flexed. Therefore, in effect, the wire cable is shortened relative to the sheathing and as the lock and circuit breaker are 15 definitely located, any change, actual or in effect, in the length of the cable wire must be compensated for in some manner. Consequently, it is the primary object of this invention to arrange the circuit breaker 20 engaging mechanism in relatively adjustable parts having, within limits, an infinite number of relatively fixed positions compensating for the shortening effect of the cable wire due to flexing of the sheathing during in- 25 stallation.

A further object is to arrange the adjustable parts so that they will under normal conditions be relatively fixed and under abnormal conditions, such as will cause changes 30 in the curvature of the sheathing, be automatically relatively adjustable thereby compensating for the slightest change in apparent length of the sheathing.

In the drawings:

35 Figure 1 is a side elevation illustrating the relative relation of the parts when installed.

Figure 2 is a longitudinal sectional view of the circuit breaker engaging mechanism.

Figure 3 is a longitudinal sectional view 40 showing the interior of the remote control key operated lock casing.

Figure 4 is a sectional view taken on the line 4—4 of Figure 2.

Like parts are identified by the same reference characters throughout the several views.

The breaker mechanism is fully disclosed in the companion application previously noted and is not, therefore, disclosed herein. Such mechanism is enclosed by a casing 10 (shown fragmentarily) and from which projects a tubular housing 11. Within the tubular housing is fitted a bushing 12 which serves as a bearing or guide for the plunger 13. The plunger is provided with an enlarged head 14 receivable in opening 15 in the casing 50 cover 16. Adjacent the head 14 is a dielectric spool 17 held in contact therewith by the nut 18. The spool 17 engages the circuit breaker arm (not shown).

Secured in any suitable manner to the 60 plunger 13 is a tubular extension 20 having an annular collar 21 on its interior intermediate the ends thereof. The collar 21 serves as a slide bearing for the rod 22 which is movable telescopically relative to the extension 20. This rod is provided with a stop flange 23 adapted to abut the collar 21 and with an axially disposed hole 24 receiving an end of the cable wire 25. Holes 26 are provided transversely of the rod 22 and intersecting the hole 24. The end 27 of the cable wire is bent at 28 and 29 into the respective holes 26 thereby to anchor the end to the rod 22. Disposed about the rod 22 is a split friction band 30 held in engagement with the rod 65 by a contractile split spring clutch 31. The friction band and spring clutch are positioned within the tubular extension 20 and are held against axial movement relative thereto by the collar 21 and the cap 32 which 70 is secured to the tubular extension in a suitable manner such as indicated at 33.

Secured to the housing 11 is a tubular fitting or shield 35 closed at one end by a core or plug 36 in which the outer flexible sheathing 37 is anchored. The outer flexible sheathing encloses the inner flexible sheathing 38. The cable wire 25, and the flexible sheathing 37 and 38 extend, as indicated in Figure 1, 85 to the lock housing 40 which is positioned in 90

an automobile dash (not shown). The outer flexible sheathing is secured to the housing 40 through a plug or core 41 and the cable wire 25 is secured to the plunger cylinder 42 which may be reciprocated by appropriate mechanism (not shown in detail) operated from the key controlled lock 43. The cable wire reciprocating mechanism is shown and described only in so far as it is necessary to illustrate some means for reciprocating the cable wire 25.

As illustrated in Figure 1, when the ignition circuit control mechanism is installed, the sheathing 37 enclosing the cable wire 25 describes a tortuous path and as a result the several successive coils of the sheathing arrange themselves angularly relative to adjacent coils. When the axis of the sheathing is disposed in a straight line, the several coils are in contact with and parallel to adjacent coils. Therefore, when the axis of the sheathing is disposed in a curved line, the coils will, as illustrated, lengthen the axis of the sheathing. It is apparent, then, that the effect produced upon the cable wire is much the same as though it were shortened. In order to compensate for this difference, the foregoing described clutch elements connecting the cable wire with the plunger 13 is provided.

The spool 17 must at all times be in proper relation to the circuit breaker arm (not shown) and the clutch elements assure this relation. Assuming that the cable wire and spool are properly adjusted before the circuit control mechanism is installed, then when such mechanism is installed, the wire, in order to compensate for the lengthening of the sheathing axis, will pull the spool toward the casing 10. Proper adjustment of the spool 17 may again be secured by operating the lock 43 to draw the clutch end of the cable wire further into the sheathing 37. This will draw the capped end of the tubular extension 20 into contact with the plug 36 which defines the limit of movement of the extension in that direction. Further inward movement of the cable wire will draw the rod 22 outwardly axially of the extension 20, the clutch or friction band 30 engaging the rod 22 with sufficient pressure only to hold the rod and extension in relative adjustment under normal conditions.

If the axis of the sheathing 37 shortens for any reason, proper adjustment of the cable wire relative to the spool 17 will be secured by manipulating the lock 43 to extend the end 27 of the wire to its maximum distance exteriorly of the sheathing. This will move the extension 20 into contact with the bushing 12 and will cause the rod 22 to move through the friction band 30 at sufficient distance to secure proper relation between the wire 25 and spool 17.

The foregoing noted mechanism, as illustrated in the drawings, provides a simple,

efficient and novel means of automatically adjusting the ignition control elements to compensate for variations in the distance between a circuit control switch and its remote key operated lock for the ignition control elements. Although I have disclosed but one embodiment of my invention, it nevertheless, is recognized by me that modifications may be devised without departing from the spirit of this invention, the result accomplished by the invention being the infinite number of relative adjustments that may be secured.

I claim:

1. In a device of the character described, the combination with a cable, a cable actuator, a control actuator and a flexible sheath subject to relative variation in length with respect to said cable, of means for connecting said cable to said actuators, and self adjusting means in one of said connections to compensate for such relative variation.

2. In a device of the character described, the combination with a handle device provided with a supporting guide, a remote device to be controlled thereby provided with a supporting guide, a control wire connecting said devices along a path variable as to length with respect to the length of said wire, and self adjusting means connecting said wire with one of said devices, whereby to compensate for such relative variation.

3. In an ignition circuit control device the combination of a circuit breaker actuator, a key operated lock remote from said actuator, an axially movable cable controlled by said lock, and means connecting said cable with said actuator, said means including an extensible member, whereby to secure substantially accurate adjustment and control of said arm from said lock.

4. In an ignition circuit control device the combination of a circuit breaking actuator, a key operated lock remote from said actuator, an axially movable cable controlled by said lock, and self adjusting means connecting said cable adjustably to said actuator.

5. In an ignition circuit control device the combination of a circuit breaking actuator and a key operated lock remote from said actuator, an axially movable cable controlled by said lock, a flexible sheath for said cable subject to relative variation in length with respect to the cable, and clutch means frictionally engaging said cable with said actuator.

6. In an ignition circuit control device, the combination of a circuit breaker arm actuator and a key operated lock remote from said actuator, an axially movable cable controlled by said lock, an axially movable arm engaging member, means defining the extent of axial movement of said member, and clutch members frictionally engaging said cable with said arm engaging member.

7. In an ignition circuit control device in-

- cluding a circuit breaker arm and a key operated lock remote from said arm, the combination with an axially movable cable controlled by said lock, of an axially movable arm engaging member, a tubular extension carried by said member, a rod movable longitudinally within said extension and secured to said cable, a friction band engaging said rod, a contractile spring clutch holding said band in engagement with said rod, and means confining said band and clutch within said tubular extension, whereby said cable and member are axially relatively adjustable. 5
8. In an ignition circuit control device including a circuit breaker arm and a key operated lock remote from said arm, the combination with an axially movable cable controlled by said lock, of an axially movable arm engaging member, a tubular extension carried by said member and movable therewith, means defining the limit of movement of said extension, a rod movable longitudinally within said extension and secured to said cable, a friction band engaging said rod, a contractile spring clutch holding said band in engagement with said rod, and means confining said band and clutch within said tubular extension, whereby said cable and member are axially relatively adjustable. 10
9. In a device of the character described a tubular member movable longitudinally of its axis, a rod telescopically movable in said member, and clutch elements confined within said member and frictionally engaging said rod, whereby said rod and member may be relatively adjusted and normally maintained in adjusted position. 15
10. In an ignition circuit control device including a casing enclosing a circuit breaker arm and a key operated lock remote from said arm, the combination with a flexible metallic sheathing secured to the casing and lock, of a cable enclosed by said sheathing and controlled by said lock, an arm engaging member, and self adjusting means adjustably securing said cable to said member. 20
11. In a device of the character described, the combination with a cable, a cable actuator, a control actuator subject to a predetermined load, and a flexible sheath subject to relative variation in length with respect to said cable; of means for connecting said cable to said actuators, and self adjusting means in one of said connections to compensate for such relative variation, said adjusting means comprising an extensible friction member offering to extensible movement a frictional resistance greater than said load. 25
12. In a device of the character described, the combination with a cable, a cable actuator, a control actuator subject to a predetermined load, and a flexible sheath subject to relative variation in length with respect to said cable; of means for connecting said cable to said actuators, one of said connections in- 30
- cluding an extensible portion including means resisting its extensible movement with a force greater than that required to overcome the load to which said control actuator is subject, and yieldable in response to predetermined degrees of force exceeding the resistance of said means, whereby said last mentioned connection is self adjusting to compensate for such relative variation. 35
